Primary Examiner — Jennifer Rivard(74) *Attorney, Agent, or Firm* — Myers Wolin, LLC(57) **CLAIM**

The ornamental design for a nail polish conditioner, as shown and described.

DESCRIPTION

FIG. 1 is a perspective view of the first embodiment of a nail polish conditioner showing our new design;

FIG. 2 is a front elevational view thereof;

FIG. 3 is a left side elevational view thereof, the right side elevational view being a mirror image;

FIG. 4 is a rear elevational view thereof;

FIG. 5 is a top plan view thereof;

FIG. 6 is a bottom plan view thereof;

FIG. 7 is a perspective view of the second embodiment of a nail polish conditioner showing our new design;

FIG. 8 is a front elevational view thereof;

FIG. 9 is a left side elevational view thereof, the right side elevational view being a mirror image;

FIG. 10 is a rear elevational view thereof;

FIG. 11 is a top plan view thereof; and,

FIG. 12 is a bottom plan view thereof.

The broken lines illustrate portions of the nail polish conditioner that form no part of the claimed design.
